Patented Mar. 27, 1928.

UNITED STATES PATENT OFFICE.

HANS C. HANSON, OF ALBERT LEA, MINNESOTA.

STOVE WITH FLOAT-OPERATED SHUT-OFF VALVE.

Application filed April 4, 1927. Serial No. 180,780.

This invention relates to a stove adapted to use liquid vaporizing fuel such as gasoline, and while the device is applicable to various stoves of this type, it particularly is 5 designed for such a stove which is assembled on a permanent and rigid frame. With such stoves as now generally constructed, liquid fuel is vaporized and suitably mixed with air to form a combustible mixture which mixture is then supplied to the burners. The fuel is commonly fed from the fuel tank either by gravity or by having the fuel in the tank under pressure. It is possible that the flame of the burners could be 10 extinguished without the supply of fuel being turned off. If this should occur, the fuel continuing to run to the burners would be vaporized and a combustible mixture would form about the stove. This would 15 be dangerous as the same might be ignited and cause a damaging explosion. It is desirable, therefore, to have some means for shutting off the supply of fuel from the fuel tank if for any reason the burners of the 20 stove should be extinguished.

It is an object of this invention, therefore, to provide a simple and efficient means for shutting off the supply of fuel from the fuel tank if the flame should become extinguished without said supply of fuel being 25 shut off at the tank.

It is another object of the invention to provide a structure of stove using liquid vaporizing fuel having means for collecting 30 any unburned liquid fuel delivered to the stove and means operated by said unburned fuel for shutting off the supply of fuel at the source of fuel supply.

It is a further object of the invention to 35 provide a stove using liquid vaporizing fuel having a fuel supply conduit and a starting means for said stove to which fuel is supplied, together with means for collecting any fuel which might be delivered to said 40 means when the stove is not lighted, and automatic means for shutting off the supply of fuel to said stove upon the accumulation of an appreciable amount of said unburned fuel.

These and other objects and advantages of the invention will be fully set forth in the following description made in connection with the accompanying drawings, in which

like reference characters refer to similar parts throughout the several views and in 55 which:—

Fig. 1 is a plan view of the stove;

Fig. 2 is a vertical section taken substantially on line 2—2 of Fig. 1, certain parts being further broken away and also shown in 60 vertical section;

Fig. 3 is a section taken substantially on line 3—3 of Fig. 1;

Fig. 4 is a vertical section taken on line 65 4—4 of Fig. 5;

Fig. 5 is a vertical section taken on line 5—5 of Fig. 1, said sections being taken as indicated by the arrows;

Fig. 6 is a view partly in side elevation and partly in vertical cross section of the 70 pump used.

Referring to the drawings, a stove is shown comprising a top plate 10 preferably made of sheet metal, the same being substantially of rectangular shape with rounded 75 corners and having a downwardly extending peripheral flange as shown. The top plate 10 is supported upon a plurality of legs 11 shown as four in number and while these legs may be variously formed, in the embodiment of the invention illustrated they are shown as in the form of angle members. A casing 12 also preferably formed of sheet metal extends about three sides of the stove, 80 said casing having inturned horizontal 85 flanges at its top, to which the top plate 10 is secured by the headed and nutted bolts 13. A pair of angle-shaped members 14 extend across the front of the stove between the front legs 11, immediately under the top 90 plate 10 and adjacent the bottom of casing 12 respectively. The top plate 10 has spaced openings 10^a. A manifold 15 is secured to the portion of the top plate 10 between the openings 10^a, by the headed and nutted bolts 16 extending through said top plate and lugs at the top of said manifold. Said manifold supports 95 burners 17 disposed respectively beneath the openings 10^a. Said manifold comprises a mixing chamber portion 15^a into which air 100 is admitted through the opening 15^b in one side of said manifold. Said manifold also has conduits 15^c leading from the mixing chamber to the burners 17. The manifold 15 has a shallow pan 15^d at its upper side beneath the vaporizing tube 18 and immedi- 105

ately in front of the mixing chamber 15^a. An opening 15^f extends from the pan 15^e into the mixing chamber, the bottom of pan 15^e continuing into said chamber and having an opening 15^g in the bottom thereof. A rod 15^d is secured in one end of the manifold 15 and projects through one end of casing 12, assisting in supporting said manifold. The fuel is supplied to the mixing chamber 15^a through a vaporizing tube 18 having a shut-off and regulating valve therein controlled by a hand wheel 19. The burner 17, remote from vaporizing tube 18, is controlled by a valve on rod 17^a having an operating hand wheel 17^b thereon disposed at the front of the stove. The fuel for the stove is contained in a tank 20 and passes from said tank through a conduit 21, said conduit passing through a valve member 22 to be later described, from which leads a conduit 25 which communicates with the under side of said vaporizing tube 18 as shown in Fig. 2. The conduit 21 is provided with a valve 24 equipped with a removable operating handle member 25, and a pressure gauge 26 extends from one side of the conduit 21 adapted to indicate the pressure on the fuel in tank 20. The tank 20 is also provided with a filling opening closed by a plug 27 having a handle shown in the shape of a star wheel. The tank 20 also has a quantity or depth gauge 20^a at one end and has a lug 20^b bored and threaded to receive a pump cylinder 28 in which moves a piston rod 28^a secured thereto, moving through a cap 28^b of the cylinder 28 and having an operating handle 28^c at its outer end. The cylinder 28 is also provided with a relief passage 28^d having a closing valve 28^e. A small tube 28^f extends from the relief passage 28^d along the side of the cylinder 28 and communicates with the lower end thereof. A check valve 30 is disposed at the bottom of cylinder 28, being held in place by a plug 31. A conduit 32 extends from conduit 23 and the vaporizing tube 18 below the latter to a bracket 33, said bracket being bolted to the flange of the upper channel 14. The bracket 33 supports a small tube 34 secured therein and projecting somewhat loosely into an opening 35^a in a Bunsen member 35, said member having a U-shaped passage 35^b with an opening 35^c directed upwardly below the conduit 34. A rod 36 also extends from bracket 33 to the member 35 for supporting the latter. It will be noted that the opening 35^c is also disposed below the vaporizing tube 18 and above the pan 15^e. The tube 34 has a regulating valve therein carried on a rod 34^a operated by a hand wheel 34^b.

The manifold 15 has a threaded aperture in its bottom, below opening 15^g, in which is secured a plug 37. Plug 37 has an open ended bore extending therein and it will be noted that said plug extends an appreciable distance above the bottom of the manifold 15. Said plug has a small aperture 37^a extending into the bore thereof substantially flush with the bottom of manifold 15. A conduit 38 extends into one side of the plug 37 communicating with the bore thereof and is connected to one end of a float casing 39 secured to the rear wall of the casing 12 below the top of float 10. The casing 39 has a float chamber therein in which is disposed the float 40. While this float may be of various shapes in the embodiment of the invention illustrated it is shown as in the form of a cylinder having a lug 40^a at its top in which is secured a lever rod 41 extending to a block 42 pivoted on a pivot pin 43 extending transversely of said casing. The block 42 has transverse and longitudinal intersecting slots in its upper side and the flattened end of the plunger 44 extends into the longitudinal slot therein, having trunnion pins 45 projecting at each side and disposed in the transverse slot in said block. The plunger 44 is rounded at one end and slides in a bore in a block 46 into which is threaded an extension 22^a from the casing of the valve 22, the end of the block 46 engaging one end of the float casing 39 and a jamb nut 47 being threaded on the casing of the valve 22 and engaging the outer side of the casing 39. A pin 44^a of considerably smaller diameter than the plunger 44 projects therefrom through an aperture in block 46 and the extension 22^a. The pin 44^a is adapted to engage a valve member 22^b of angular cross section and which is illustrated as hexagonal in cross section, said member 22^b being slideable in a bore in casing 22 and having a recess at the end opposite pin 44^a, which recess is filled with some rather soft material 22^d such as cork. The member 22^b is threaded into the end of casing 22 and has a passage extending therethrough surrounded at one end by a comparatively sharp flange 22^d forming a valve seat with which the material 22^d in valve 22^b engages. The conduit 21 is coupled to one end of the member 22^c by the usual threaded sleeve coupling and the conduit 23 is similarly coupled to one side of the valve casing 22. The casing 29 has a removable cover 39^a secured to the top thereof. The casing 12 has angular members 48 secured at each end thereof having one flange extending downwardly and inwardly and angular members 49 are secured to the members 48 beneath said latter flange, thus forming guideways 50 into which a catch pan may be slid into the casing 12 beneath the manifold 15 and burners 17.

In operation the fuel in the tank 20 will be placed under pressure by pumping the air into said tank by means of a pump operated by handle 28^c. The fuel passes up into conduit 21 and the float 40 being in its low po-

sition as shown in Fig. 3, the valve plunger 22^b will be forced out of contact with member 22^c. The fuel can thus pass through the member 22^c, casing 22 and through conduit 23 to the vaporizing tube 18. The fuel also passes, under pressure, through conduit 33 and into the conduit 34. To ignite the stove a small flame, such as that furnished by an ordinary match, is held beneath the small tube or conduit 34. The fuel in this tube will be vaporized, and valve wheel 34^b can then be manipulated to open the valve in tube 34. The vaporized fuel will pass into member 35, being mixed with some air and will pass up through opening 35^c where it will be ignited by the match held under tube 34. The flame passing up from opening 35^c will continue to heat tube 34 so that a blue or Bunsen flame will be maintained rising from the opening 35^c and this flame will also extend upwardly and heat the vaporizing tube 18. After this flame has operated for a short time, the hand wheel 19 may be turned to open the valve in vaporizing tube 18 and burner 17 adjacent hand wheel 19 may then be lighted. After the burner 17 is lighted, the valve in tube 34 may be closed by hand wheel 34^b. The vaporized fuel passes through tube 18 into the mixing chamber 15^a and air is drawn into this mixing chamber through the opening 15^b. The combustible mixture thus formed passes through the passage 15^c to the burner 17. If it is desired to ignite the other burner 17, the hand wheel 17^b will be turned to permit the combustible mixture to flow to said burner.

If for any reason the flame on the burner should become extinguished or the tube 34 should be left open so that fuel would be supplied to tube 34 or vaporizing tube 18, the stove would automatically be shut off. Any unburned fuel passing into member 35 would overflow therefrom into the pan 15^c. This fuel would pass into the mixing chamber and through opening 15^c to the bottom thereof and would then flow into the member 37 and through conduit 38 to the float casing 39 and would accumulate therein. Any unburned fuel passing into the vaporizing tube 18 would also drip into the the mixing chamber and pass through opening 15^c to the bottom of the mixing chamber and into the member 37. This fuel would then pass through the conduit 38 to the float casing 39. The fuel accumulating in the float casing would raise the float 40, thus raising the lever 41 and swinging block 45 towards casing 22. The plunger 44 would slide in the block 46 and the pin 44^a would push the member 22^b against member 22^c. The cork or soft material insert in the plunger 22^b would tightly close the passage in member 22^c. The fuel is thus shut off from conduit 23 and no further fuel can then flow to vaporizing tube 18 or to the tube 34. No

great amount of gasoline could thus be furnished to the stove in an unburned condition and there is no danger of this unburned fuel evaporating and forming a combustible mixture of any appreciable volume. The plunger 44 is made larger than the pin 44^a to form a good guiding surface to operate the slideable plunger valve 22^b. The plug 37 is constructed to stand some distance above the bottom of the manifold and the opening 37^a is provided therein so that there is always a draft upward through said plug. This prevents the combustible mixture in the manifold from passing out through said plug and conduit 38 where it might collect and become ignited. It will be understood that the burners 17 create quite a draft through the manifold. The pressure on the fuel in the tank 20 will be indicated on the gauge 26 and the depth of the fuel will be shown on the depth gauge 20^a.

From the above description it is seen that applicant has provided a very simple and efficient structure of stove and one having means for positively shutting off the fuel supply when the stove burners are extinguished without the supply of fuel being turned off or when the supply of fuel is turned on without the burners being lighted. The stove is thus safe and there is no danger of an explosion caused by a large volume of combustible mixture being formed adjacent the same. The parts of the device are quite few and simple in construction. The stove is quite rugged in construction. The same has been amply demonstrated in actual practice and found to be very successful and efficient.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

1. A stove adapted to use liquid vaporizing fuel having in combination, a fuel tank, a burner, a mixing chamber for supplying a combustible mixture to said burner, a member supplying fuel to said mixing chamber and burner, a manually operated valve regulating the supply of fuel to said member, an auxiliary starting burner of the retort type, means for supplying fuel thereto, a manually operated valve controlling the supply of fuel to said auxiliary burner, and automatic means operated by liquid fuel for shutting off the supply of fuel from said fuel tank if either of said manually operated valves are left open with its respective burner not ignited.

2. A stove adapted to use liquid vaporiz-

- ing fuel having in combination, a fuel tank, a main burner, means comprising a manually operated valve for controlling the supply of fuel to said burner, an auxiliary burner of the retort type, means comprising a manually operated valve for controlling the supply of fuel to said auxiliary burner, a conduit for supplying fuel from said tank to both of said means, a valve in said conduit, a float chamber, means for collecting unburned fuel from both of said burners and directing the same to said float chamber, a float in said chamber, and means connected to said float and to said valve for positively closing said last mentioned valve when either of said manually operated valves are left open with their respective burners not ignited.
3. A stove adapted to use liquid vaporizing fuel having in combination, a fuel tank, a burner, a mixing chamber for supplying combustible mixture to said burner, means comprising a manually controlled valve for supplying fuel to said mixing chamber, a float chamber, means for collecting unburned fuel and directing the same into said mixing chamber, a member having an open upper end in said mixing chamber extending above the bottom thereof and having a chamber therein, and having an opening into said chamber substantially flush with the bottom of said mixing chamber, a conduit connecting said member to said float chamber, a conduit for supplying fuel to said last mentioned means, a valve in said last mentioned conduit, and means connected to said float and said last mentioned valve for closing said last mentioned valve when liquid fuel accumulates in said float chamber.
4. A stove adapted to use liquid vaporizing fuel having in combination, a fuel tank, a burner, a mixing chamber for supplying a combustible mixture to said burner, a conduit for supplying fuel from said tank to said mixing chamber, a float chamber, a float in said chamber, a conduit for conveying unburned fuel from said mixing chamber to said float chamber, a tubular member communicating with said conduit having an open end disposed an appreciable distance above the floor of said mixing chamber and having an opening thereinto substantially flush with the floor of said mixing chamber, whereby a draft is caused upward in said member preventing the flow of combustible mixture to said float chamber, and means adapted to be actuated by said float for shutting off said first mentioned conduit upon accumulation of liquid fuel in said float chamber.
5. A stove adapted to use liquid vaporizing fuel, having in combination a frame, a fuel tank carried thereon, a manifold comprising a mixing chamber, burners carried on said manifold, a vaporizing tube for supplying fuel to said mixing chamber and burners, an auxiliary starting burner disposed below said vaporizing tube, a conduit connected to said tank and to said vaporizing tube and auxiliary burner, a receptacle disposed beneath said auxiliary burner and at the top of said manifold having a drain means, a float chamber on said frame, a conduit connecting said float chamber to the bottom of said mixing chamber, said drain means communicating with said mixing chamber and last mentioned conduit, a float in said float chamber, a valve in said first mentioned conduit, for shutting off the supply of fuel from said tank to said vaporizing tube or auxiliary burner, and means connected to said float and to said valve for positively moving the same to open or closed position.
6. A stove adapted to use liquid vaporizing fuel having in combination, a frame, a fuel tank carried thereon, a manifold comprising a mixing chamber and a plurality of burners carried thereby, a vaporizing tube connected to said mixing chamber, an auxiliary starting burner disposed below said vaporizing tube, a conduit connected to said fuel tank and to said vaporizing tube and auxiliary burner, a pan carried by said manifold beneath said auxiliary burner and having a drain opening leading into said mixing chamber, a float chamber carried on said frame, a conduit leading from the bottom of said mixing chamber to said float chamber, a valve in said first mentioned conduit for shutting off the supply of fuel to said vaporizing tube and auxiliary burner, and means connected to said float and to said valve for positively moving the same to closed and open position respectively as said float rises or falls.
7. A stove adapted to be supported on a table or similar support having in combination, a frame comprising a top plate having a plurality of openings therein, a fuel tank supported at one end of said frame, a manifold comprising a mixing chamber, main burners connected to said manifold and vertically aligned with said openings, a vaporizing tube extending across the top of the main burner nearest said tank, the conduit connecting said vaporizing tube and tank, a manually operated valve controlling said conduit, an auxiliary starting burner disposed beneath said vaporizing tube at one side of said main burner, a small conduit extending to said auxiliary burner, a manually operated valve for controlling said last mentioned conduit, a conduit connecting said conduits, a float chamber on said frame, a float therein, a valve controlled by said float for closing said first mentioned conduit, a drain conduit leading from said man-

ifold to said float chamber, and a drain means extending from said auxiliary burner to said manifold.

8. A stove adapted to use liquid vaporizing fuel having in combination, a fuel tank, a manifold comprising a mixing chamber, a burner to which a combustible mixture is supplied from said manifold, a vaporizing tube for supplying fuel to said mixing chamber, a conduit connecting said tank and vaporizing tube for supplying fuel to the latter, a shut-off valve for said vaporizing

tube, an auxiliary starting burner of the re-tort type for said burner, means for supplying fuel to said auxiliary burner, a shut-off valve for said auxiliary burner and automatic means operated by liquid fuel for shutting off the supply of fuel from said fuel tank if either of said shut-off valves are left open with its respective burner not ignited.

In testimony whereof I affix my signature.

HANS C. HANSON.
